UNITED STATES PATENT OFFICE.

ALBERT F. SAWYER, OF HAVERHILL, MASSACHUSETTS, ASSIGNOR TO IRVING L. KEITH, OF HAVERHILL, MASSACHUSETTS.

REFRIGERATING SYSTEM.

Application filed July 28, 1925. Serial No. 46,582.

In providing automatic refrigeration for apartments in a single building, where it is undesirable and unduly expensive to provide a complete refrigerating system for each apartment, it is desirable to have the refrigerant supplied automatically by a single motor driven compressor when a system of the compressor, condenser, expander type of refrigeration is employed. It has been attempted to accomplish this result by providing a main distribution pipe, which leads from the condenser and from which branch pipes lead to the several refrigerating units, and to control the supply to various refrigerating units by means of automatic valves.

While this method of distribution is reasonably satisfactory when employed in connection with refrigerating units of large capacity which are under direct supervision or control, particularly when the units are placed at nearly the same level, and, while, theoretically, the desired result of a satisfactory system, which is entirely automatic, may be secured by means of various forms 25 of automatic valves designed to control the supply of refrigerant from the main pipe to the unit according to predetermined requirements, yet, so far as I am aware, these systems have been found to be unsatisfactory, 30 particularly because some of the units were liable to be insufficiently supplied with liquid refrigerant, this difficulty being particularly great when the refrigerating units were located at different elevations.

The object of my invention is to provide a refrigerating system of the type above referred to in which a series of refrigerating units may be effectively supplied by a single 40 compressor, the temperature in each unit of which is to be maintained at a predetermined mean point, whatever the requirements, within reasonable limits, which are placed thereon, and the system to be adapted to permit any one of the units to be cut 45 out of the system without disturbing the operation of the other units.

In this connection, another object of the invention is to provide a system in which the entrance, to any substantial extent, of refrigerant in gaseous form to the cooling tank, or expansion chamber, is prevented and the entrance of liquid refrigerant only is permitted.

I accomplish these objects by providing, 55 in connection with any ordinary form of

motor driven compressor, a series of surface condensers, or condensing coils corresponding in number to the number of expansion units to be supplied, connecting said coils to each other and to the discharge port of the compressor at their inlet ends separately connecting each coil at its discharge end to the expansion chamber of the corresponding cooling unit through an automatic apparatus which prevents the passage of gaseous 60 refrigerant and permits the passage of liquid refrigerant thereto, under certain conditions, connecting the outlet from each expansion chamber to the inlet of the compressor, and by providing, in connection therewith, a 65 single regulating means for the motor for driving the compressor, so that when the pressure of the refrigerant at the inlet to the compressor is raised to a certain point, the motor will be started, and, when it is lowered to a certain point, the motor will 70 be stopped.

For a more complete and detailed description of the system embodying my invention reference is made to the accompanying 75 drawing in which:

Fig. 1 is a diagrammatical view of a closed circuit refrigerating system embodying my invention, and

Fig. 2 is a detail view of a compressor and condenser connection which I may employ.

Figs. 3 and 4 are detail sectional views of an inlet control device for the expansion chambers which I employ and

Fig. 5 is a detail view of a form of valve which is employed in connection therewith.

As certain apparatus, which is employed in connection with the refrigerating system hereinafter described, is well known in systems of the type above indicated, such apparatus has been conventionally illustrated.

As indicated, the motor 1 has a main shaft, on which a cooling fan 3 is mounted, said shaft being arranged to operate a compressor pump 4, from which a discharge pipe 5 leads.

According to my invention, I provide a plurality of surface condensers or condenser coils 6, 7, 8 corresponding in number to the particular number of independent refrigerating units to be employed, the particular number of units shown being merely illustrative, and connect the upper or inlet end of each coil to a casing 9, into which the

discharge pipe 5 from the compressor also opens, so that each condenser coil is in open communication with the others and with the discharge pipe from the compressor, at its 5 inlet end, and extends downwardly to its outlet from this point.

A corresponding plurality of refrigerating units are provided, each of which, comprises an expansion chamber or refrigerant 10 tank, as 10, 11 and 12, and as said tanks will, in practically all instances, be located at a higher elevation than the condenser coils, the system being of special advantage in such a relation, they are so indicated in 15 the drawing. The tanks are respectively connected to the lower, or outlet ends of the corresponding coils 6, 7, and 8 by conducting pipes 13, 14 and 15, the connection thereto in each instance being made through an 20 automatically controlled valve, which is illustrated in detail in Figs. 3, 4, and 5, and which I have especially designed for the purpose, the same form of valve device being employed for each refrigerating unit.

25 The device comprises a container 16 having a cover 17, which has a gas tight connection therewith, said cover having an inlet passage 18 and outlet passage 19, said inlet passage opening to the container close to 30 the side wall thereof and having a conducting pipe, as 13, connected thereto, and said outlet passage being connected to an expansion tank by a pipe 20. A pipe 21 is connected to the cover 17, in communication 35 with the outlet passage 19, and depends therefrom, the lower end of said pipe being open and a valve seat 22 being provided in the passage 19. A metal cup 23 is provided within the container and is mounted to tilt 40 therein on a pivot 24, which, for convenience, is supported by the pipe 21 at its lower end. A needle valve 25 is connected by a pivot pin 26 to the bottom of the cup 23 and extends upward in the pipe 21 into position to 45 seat against the seat 22, when the cup is in its horizontal position. The conical upper end of the needle valve 25 is provided with a leak passage 27, for purposes to be explained, and as indicated in detail in Fig. 5. 50 Return pipes 28, 29 and 30 are respectively connected to the top portions of the tanks 10, 11 and 12, said pipes being in turn connected to a single return pipe 31 which leads to the intake end of the compressor, so that 55 a closed fluid circuit is formed through each tank. A pressure regulator 32 is provided in the return pipe 31, which is arranged to operate the control switch of the motor, so that, when the gas pressure varies to a pre- 60 determined extent from normal the motor will be started or stopped as the case may be. That is, when the gas pressure of the refrigerant in the refrigerating tanks is at a certain point, the temperature of the liquid refrigerant therein will be at a certain point,

and, as the gas containing chambers in each tank are all connected to the common return pipe, the gas pressure in all the tanks and in the return pipe will be practically the same. The temperature of the liquid refrigerant in all the tanks will consequently be the same, and any increase in gas pressure in any one of the tanks will be immediately transmitted to all the other tanks and to the return pipe, so that when this pressure is 70 raised above the predetermined limit, the motor will be started, and, when the pressure is lowered to the desired extent, the motor will be stopped.

80 Suitable shut-off valves 33 will be provided at the inlet end of each condensing coil, and in the discharge pipe of each expansion tank, so that, when use of any one of the refrigerating units is to be discontinued, the corresponding valves 33 will be closed, and 85 the normal operation of the other units will not be interfered with, operation being resumed in the unit by merely opening these valves.

When the system is to be started each 90 refrigerating tank will be filled with a suitable quantity of liquid refrigerant, as methyl chloride, and the other portions of the system will be filled with gaseous refrigerant, all 95 air being expelled from the system as far as possible.

The shut-off valves having been opened, the operation is as follows:—

In the normal operation of the system, when, by reason of increase in temperature 100 of the refrigerant in the expansion tanks, and consequent increase of gas pressure therein, and in the return pipe 31, the motor is started, the action of the compressor in forcing gaseous refrigerant into all of the 105 condenser coils will be the same, as their inlet ends are all in open communication with the discharge pipe of the compressor and with each other. All the coils are arranged so that they are practically under 110 the influence of the cooling means, which, as herein shown, is an air cooling means, but which, obviously, may be any other suitable means, although the air cooling means is preferred, one of the advantages of the present system residing in the fact that it enables 115 the use of an air cooling system.

By the action of the compressor, the gas pressure will be raised uniformly in all the condenser coils and all the containers 16 and 120 the pipes connecting the coils and the containers.

While, in starting up the system originally, no liquid refrigerant may be contained 125 in the cups 23, so that gas may pass from the containers 16 to the refrigerating tanks, yet the size of the outlet passages 19 from the containers is relatively small, as compared with the volume of gas delivered by the compressor, so that pressure will be im- 130

mediately built up in the containers to an extent sufficient to cause the condensing operation to begin, and condensation to take place in all the coils, containers and connecting pipes. The liquid formed in the coils will accumulate in the lower portions thereof until the passage of gas is prevented, and then the pressure behind this liquid will force "slugs" of the liquid up the conducting pipes 13, 14, 15 until it is discharged through the passages 18 of the containers and falls therein. The passage 18 of each container is so located that liquid passing therethrough will not be discharged directly into the cup 23, but only into the container at one side thereof, so that, as the condensing process continues, the container will be filled until the cup 23 is lifted by its buoyancy to its horizontal position shown in Fig. 4, closing the valve 25. The container will then be filled until the liquid overflows into the cup 23 and fills the same to such an extent that its buoyancy is insufficient to sustain it in the position of Fig. 4, so that it swings down to the tilted position of Fig. 3, thereby opening the valve 25, and permitting the gas pressure on the surface of the liquid in the cup to cause the liquid therein to be forced up the pipe 21 through pipe 20 into the expansion tank to which it is connected. This will continue until the cup is emptied to such an extent that its buoyancy is sufficient to restore it to its initial, or horizontal position and close valve 25. As at this time the container will be filled to the level of the edge of the cup, indicated by the line X in Fig. 3, the cup will be lifted by its buoyancy by the time the liquid level therein has been lowered approximately to the level of line y in Fig. 4, so that the lower end of the pipe 21 at no time will become unsealed. If the operation of the compressor is continued, the container will be filled again until the liquid overflows into the cup again, so that it sinks and the above described operation is repeated.

This operation will continue until the deficiency of liquid refrigerant has been supplied and the temperature thereof has been reduced by reason of the reduction in pressure of the gas in the refrigerating tanks, caused by the suction action of the compressor. As the action of the compressor in forcing gas into the condenser coils is uniform, the quantity of liquid refrigerant supplied to each refrigerating tank will be practically constant, and, as the temperature of the refrigerant in each tank will be the same, by reason of the uniform gas pressure therein, the refrigerating effect of all the tanks will be practically the same. This is assuming that the tanks are of approximately uniform size, but if one tank was considerably larger than the rest and the demands thereon were correspondingly greater the capac-

ity of the means for supplying refrigerant thereto would be correspondingly increased.

The above described operation of supplying liquid refrigerant to the tanks will continue until the pressure on the return side 70 of the circuit is reduced to the predetermined point and then the pressure regulator will automatically open the switch and stop the motor. When the motor stops the pressure in the supply side to the tanks will be 75 considerably greater than that in the return side, so that, ordinarily, this pressure will be sufficient to force liquid remaining in the cups 23 up the pipes 21 until the cups lift by their buoyancy and close valves 25. The 80 "leak" passage 27, which is provided in each valve, permits the liquid remaining in the cup, to be forced therefrom until the pipe 21 becomes unsealed and then gas and liquid will be permitted to escape past valve 25 into 85 the tanks until the pressure in the supply and return sides of the system is equalized, the quantity of gas thus escaping being practically insignificant. This is an advantageous feature of my invention, as the pressure on each side of the compressor will thus be equalized within a few minutes after the motor stops, so that when the motor is started again the load thereon will be practically 90 nothing more than friction. This enables a motor of low torque to be employed, which has important advantages. Also, in filling the system, while it is the intention to remove the air therein as completely as possible, yet, to do this is somewhat difficult, so 95 that a substantial quantity of air is frequently left therein, and if the refrigerant gas is somewhat heavier than air, any air in the system is liable to accumulate in the highest portion thereof, particularly in the 100 uppermost container. Under such conditions the container might be filled with liquid refrigerant sufficiently to lift the cup 105 therein and close the needle valve, and then, if the portion of the container above the liquid level were filled with air and the valve was tightly closed, the air would prevent the entrance of more refrigerant so that circulation through the unit would be prevented. By providing the leak passage 27, air 110 accumulating in a container 16 will be permitted to escape to the return side of the circuit, so that it will not materially interfere with the operation of the system.

The above described apparatus is advantageous over the ordinary expansion valve for admitting refrigerant to the refrigerating tanks, in that such valves are liable to permit the passage of gas with the liquid to the refrigerating tanks which is the cause of 115 substantial waste, and if such valves become leaky further waste is caused, as the ordinary expansion valve must close tightly in order to operate efficiently. It is practically impossible for a supply apparatus for the 120 125

tanks such as above described to get out of order while the ordinary expansion valve is liable to become inoperative.

With the above described construction the supply of liquid refrigerant to each refrigerating tank is practically uniform, for the reason that the supply of gaseous refrigerant to each pipe which conducts the refrigerant thereto is constant, and this distribution 10 would not be uniform if it were made after the refrigerant begins to liquefy. As the expansion chambers of all the chambers are connected so that the pressure therein is uniform, any increase of pressure in any one 15 tank is immediately transmitted to the others, so that each tank may act as a reserve for the others and as the pressure and quantity of liquid refrigerant in each tank is uniform the temperature therein will be 20 kept uniform.

While the refrigerating units in the above described system are illustrated as located at different elevations above the compressing and condensing apparatus, under which conditions it is particularly advantageous, it is to be understood that it would be equally 15 advantageous if the compressing and condensing apparatus were located above the refrigerating units. However conditions 20 where such an arrangement would be desirable are very unusual. The system is also 25 advantageous where all the units are on the same level as the said apparatus, but the difficulties of single pipe distribution under 30 such conditions are not as great as when the units are at different levels. It will also be 35 understood, that, while the particular form of apparatus above described, for admitting liquid and preventing the passage of gas to 40 the expansion tanks, is considered to be especially advantageous in the above described system, yet it will operate satisfactorily when used in connection with types of expansion 45 valves which employ a float in the expansion tank for regulating the supply of liquid refrigerant thereto.

I claim:

1. A refrigerating system comprising a 50 plurality of refrigerating expansion chambers adapted to contain a refrigerant, a corresponding plurality of surface condensers, a separate connection between the discharge end of each condenser and its corresponding expansion chamber, a compressor having its 55 discharge in open communication with the inlet end of each condenser and return connections placing said expansion chambers in open communication with each other and with the inlet to the compressor, forming 60 a closed fluid circuit through each condenser and corresponding chamber.

2. A refrigerating system comprising a 65 plurality of refrigerating expansion chambers adapted to contain a refrigerant, a corresponding plurality of surface condensers, a

separate connection between the discharge end of each condenser and its corresponding expansion chamber, a compressor having its discharge in open communication with the inlet end of each condenser, return connections placing said expansion chambers in open communication with each other and with the inlet to the compressor, forming a closed fluid circuit through each chamber, a 70 motor for operating said compressor, and a 75 pressure regulator for controlling said motor according to the gas pressure in said return connections.

3. A refrigerating system comprising a plurality of refrigerating expansion chambers 80 adapted to contain a refrigerant, a corresponding plurality of surface condensers, a compressor having its discharge connected to the top portion of each condenser and arranged to supply gaseous refrigerant thereto in equal volume, return pipes arranged to place said expansion chambers in open communication with each other and to connect the same to the inlet to the compressor, a closed container arranged adjacent 85 each expansion chamber, a separate conductor pipe connected to the bottom portion of each condenser and extending to a corresponding container in open communication therewith, and connections between each 90 container and the adjacent expansion chamber including automatic means normally permitting the passage of liquid from the container to the chamber and preventing 95 the passage of gas thereto.

4. A refrigerating system comprising a plurality of refrigerating expansion chambers 100 adapted to contain a refrigerant, a corresponding plurality of surface condensers, a compressor having its discharge connected to the top portion of each condenser and arranged to supply gaseous refrigerant thereto in equal volume, return pipes arranged to place said expansion chambers in open communication with each other and to connect the same to the inlet to the compressor, a closed container arranged adjacent 105 each expansion chamber, a separate conductor pipe connected to the bottom portion of each condenser and opening into the upper portion of its corresponding container, an outlet pipe opening to the bottom portion of each container and into the adjacent expansion chamber, and means for normally sealing the inlet to each outlet pipe including a valve arranged to close the same to prevent unsealing and to open the same when the container is filled with liquid to a predetermined extent, to permit the liquid 110 to be forced into the expansion chamber.

5. A refrigerating system comprising a plurality of refrigerating expansion chambers 115 adapted to contain a refrigerant, a corresponding plurality of surface condensers, a compressor having its discharge connected to 120

the top portion of each condenser and arranged to supply gaseous refrigerant thereto in equal volume, return pipes arranged to place said expansion chambers in open communication with each other and to connect the same to the inlet to the compressor, a closed container arranged adjacent each expansion chamber, a separate conductor pipe connected to the bottom portion of each condenser and opening into the upper portion of its corresponding container, an outlet pipe opening to the bottom portion of each container and into the adjacent expansion chamber, and means for normally sealing the inlet to each outlet pipe including a valve arranged to close the same to prevent unsealing and to open the same when the container is filled with liquid to a predetermined extent, to permit the liquid to be forced into the expansion chamber, said means including means to permit gradual escape of fluid from the container to its expansion chamber, for the purposes described.

6. A refrigerating system comprising a plurality of refrigerating expansion chambers adapted to contain a refrigerant, a corresponding plurality of surface condensers, a compressor having its discharge connected to the top portion of each condenser and arranged to supply gaseous refrigerant thereto in equal volume, return pipes arranged to place said expansion chambers in open communication with each other and to connect the same to the inlet to the compressor, a closed container arranged adjacent each expansion chamber, a separate conductor pipe connected to the bottom portion of each condenser and opening into the upper portion of its corresponding container, an outlet pipe opening to the bottom portion of each container and into the adjacent expansion chamber, means for normally sealing the inlet to each outlet pipe, including a cup movably mounted in the container to be raised by its buoyancy and lowered by its gravity when filled with liquid overflowing from the container, and into the bottom portion of which the outlet pipe opens, and a valve arranged to be moved to close the pipe when the cup is lifted and to open it when the cup is lowered, the conductor pipe of the container opening thereto at one side of the cup to prevent direct discharge liquid into the same.

In testimony whereof, I have signed my name to this specification.

ALBERT F. SAWYER.
